CARBURETOR

Elmer M. Bimberg, Detroit, Mich., assignor to
 Bendix Aviation Corporation, South Bend, Ind.,
 a corporation of Delaware

Application March 30, 1949, Serial No. 84,446

4 Claims. (Cl. 261—41)

1

The present invention relates to carburetors for internal combustion engines and the like, and more particularly to an improved idle system for said carburetors.

In many commercial carburetors for internal combustion engines, the fuel for engine idling is taken from the main discharge system and mixed with air usually supplied from the air horn, to form an emulsion which is then discharged into the induction passage on the engine side of the throttle valve. Under some conditions of operation, such as during high speed or high power output, the fuel and air flow in certain portions of the idling system reverse direction, permitting the air for idling to bleed into the main discharge system, thus leaning out the fuel-air mixture supplied to the engine at a time when a somewhat richer mixture is required. This reversal of flow in the idle system is caused by the high suction in the main discharge jet at a time when there is substantially no suction on the discharge ports of the idle system. It is, therefore, one of the principal objects of the present invention to provide an air supply means for the idling system which will minimize or completely prevent the reverse flow of air in the idle system. Further objects and advantages of the present invention will become apparent from the following description and accompanying drawing, wherein:

Figure 1 is a vertical cross-sectional view through the carburetor in which the idling system has been rearranged to more clearly show its relationship to the main discharge jet; and

Figure 2 is a top plan view of the main body of the carburetor taken on line 2—2 of Figure 1.

Referring more specifically to the drawing, and to Figure 1 in particular, there is shown a conventional downdraft single barrel carburetor for an internal combustion engine wherein numeral 10 designates the main body, 12 an air horn, 14 a throttle body, and 16 a fuel bowl or float chamber having a float 18 mounted therein for controlling a conventional fuel inlet valve (not shown). The throttle body 14 is secured to the intake manifold of the engine by suitable bolts extending through flange 20 and contains a throttle valve 22 mounted on throttle shaft 24 which is actuated by any conventional throttle operating means such as accelerating pedal.

The main body 10 contains a large venturi 30, small venturi 32 concentrically located in respect to the large venturi, and a fuel discharge system 34 connecting the fuel bowl 16 with the throat of the small venturi. The small venturi is held 35

in place by oppositely disposed fins 36 and 38 which are preferably cast integrally with said venturi and held in place in the main body by oppositely disposed recesses in the side wall 5 thereof.

The main fuel metering system 34 includes a main fuel well 40 connected near the lower end thereof with the fuel bowl through conduit 42, metering orifice 44 in conduit 42, and port 46 10 in the bottom of the fuel bowl, and connected near the upper end thereof with the throat of the small venturi through conduit 48 and discharge nozzle 49. Disposed in well 40 and extending from the top thereof to a short distance 15 from the bottom, is a sleeve member 50 having several vertical rows of ports 52 for admitting into the well the air delivered from the air horn through conduit 54, annular space 56, ports 58 to the internal portion of sleeve member 50. The 20 air entering well 40 through ports 52 mixes with the fuel in said well to form a fuel-air emulsion which is discharged through conduit 48 and nozzle 49 into the throat of the small venturi.

The idle system receives its fuel from the main 25 discharge jet through port 59 in the bottom of sleeve member 50 and tube 60 extending throughout substantially the entire length of said sleeve member and having a small orifice 61 in the upper end thereof for metering the fuel 30 for idling. As the fuel passes through the idle system, it is mixed with air admitted through conduit 62 at junction 64 to form a fuel-air emulsion which is discharged through the idle 35 discharge port 66 adjacent the upper edge of the throttle valve.

In conventional carburetors of similar construction, the air supplied to the idle system is delivered directly from the air horn. As the speed of the engine increases, the suction on the main discharge system in the throat of the small venturi sometimes becomes sufficiently great to cause the air flow through the idling system in the reverse direction, entering the main fuel discharge system, as for example in the present carburetor, through tube 60, port 59 and well 40, unduly leaning out the fuel-air mixture of the main fuel supply. In the present invention, this reversal of the air flow is prevented by taking the air supply for the idling system from the throat of the venturi so that as the suction 45 increases on the main discharge jet, there is a corresponding increase in suction in the opposite direction on the air supply in the idling system; consequently, the relationship of the air 50 pressure in the idling system to the pressure in

the main discharge system remains substantially constant regardless of air flow in the induction passage or suction on the nozzle of the main discharge jet. As shown in Figure 1, air supply conduit 62 of the idling system is connected with the throat of the small venturi through conduits 70 and 72 and nozzle 73. A fixed restriction 74 and a variable restriction 76 controlled by adjustable valve 78 are provided in the idling air supply conduits in order to obtain the proper amount of air for the idle system under various operating conditions.

The carburetor embodying the present invention also includes the usual additional elements found in conventional automotive internal combustion engine carburetors such as accelerating pump, power enrichment jet and choke valve.

In the operation of the present carburetor, starting with the throttle valve in closed or in substantially closed position as shown in Figure 1, the fuel for idling flows from well 40 through tube 60, metering orifice 61, thence passes to conduit junction 64 where it mixes with air admitted through conduits 72, 70 and 62 and variable restriction 76 to form a fuel-air emulsion which is discharged through orifice 66 into the induction passage adjacent the throttle valve. As the throttle valve is opened, the fuel is supplied to the induction passage by the main discharge system 34 through port 46, main metering orifice 44, conduit 42, well 40 where it mixes with air supplied through conduit 54, ports 58, sleeve 50 and ports 52 to form a fuel-air emulsion which is discharged through the main discharge conduit 48 and nozzle 49 into the throat of the small venturi. As the throttle valve is opened further and the speed of the engine and the air flow through the carburetor increases, the suction on the main discharge jet also increases. In the carburetor embodying my invention, however, there is no substantial increase in the tendency of the air to reverse its flow through the idle system and flow into the main discharge system since the suction in the small venturi on nozzle 73 of the idle air bleed increases correspondingly to that on nozzle 49 of the main discharge system, so that the effect of the suction in the main system transmitted to the idling system is balanced by the suction transmitted from the small venturi through conduits 72, 70 and 62.

Although only one embodiment of my invention has been shown and described herein, it is understood that many modifications may be made to suit requirements.

I claim:

1. In a carburetor having an induction passage, a throttle valve, a venturi, and a main discharge system communicating with said venturi and having a metering restriction constituting the last substantial restriction therein: an idle system comprising a fuel conduit communicating with the main discharge system posterior to said metering restriction and with the induction passage posterior to said throttle valve, and a passageway forming substantially the sole air supply means for said idle system communicating with said fuel conduit and with said venturi on

the same transverse plane as and in spaced relation to said main discharge system.

2. In a carburetor having an induction passage, a throttle valve, a venturi, and a main discharge system communicating with said venturi: an idle system comprising a fuel conduit communicating with the main discharge system posterior to any substantial restriction therein and with the induction passage adjacent the throttle valve, and a passageway communicating with said fuel conduit and with said venturi on the same transverse plane as and in spaced relation to said main discharge system.

3. In a carburetor having an induction passage, and a main discharge system connected to said induction passage and having a metering restriction constituting the last substantial restriction therein: an idle system comprising a fuel conduit communicating with the main discharge system posterior to said metering restriction and with the induction passage posterior to the point at which the said main discharge system is connected thereto, and a passageway forming the sole air supply means for said idle system communicating with said fuel conduit and with said induction passage on the same transverse plane as and in spaced relation to said main discharge system, said passageway and said main discharge system being so located relative to each other that substantially the same pressure is maintained therein throughout the operating range of the carburetor.

4. In a carburetor having an induction passage, a throttle valve, and a main discharge system connected to said induction passage on the air intake side of said throttle valve and having a metering restriction constituting the last substantial restriction therein: an idle system comprising a fuel conduit communicating with the main discharge system posterior to said metering restriction and with the induction passage posterior to said throttle valve, and a passageway forming the sole air supply means for said idle system communicating with said fuel conduit and with said induction passage on the same transverse plane as and in spaced relation to said main discharge system, said passageway and said main discharge system being so located relative to each other that substantially the same pressure is maintained therein throughout the operating range of the carburetor.
